UNITED STATES PATENT OFFICE

152,543

DESIGN FOR A LIGHTING FIXTURE END PLATE

Joseph O. Howard, Chicago, Ill., assignor to L. J. Segil Company, Chicago, Ill., a corporation of Illinois

Application June 17, 1947, Serial No. 139,733

Term of patent 14 years

(Cl. D48—23)

To all whom it may concern:

Be it known that I, Joseph O. Howard, a citizen of the United States and a resident of Chicago, Cook County, Illinois, have invented a new, original, and ornamental Design for a Lighting Fixture End Plate, of which the following is a specification, reference being had to the accompanying drawing, forming a part thereof.

Fig. 1 is a perspective view of a lighting fixture end plate, showing my new design;

Fig. 2 is an elevational view of said end plate;
Fig. 3 is a side elevation of said end plate.

I claim:

The ornamental design for a lighting fixture end plate, as shown.

JOSEPH O. HOWARD.
